UNITED STATES PATENT OFFICE

OVILA JOSEPH BLANCHET, OF NEW BEDFORD, MASSACHUSETTS

INDUCTION ELECTRIC FURNACE

Application filed December 16, 1930. Serial No. 502,693.

My invention relates to devices for heat treating the shanks of drills and other like tools after hardening.

The main purpose of my invention is to anneal the shank of a drill or other like tool without discoloration.

A further purpose is to anneal drill shanks, etc. in a non-oxidizing atmosphere.

A further purpose is to trap a non-oxidizing atmosphere in an annealing chamber and to insert and remove the drills to be annealed in such a way as to cause a minimum release of or interference with this atmosphere.

A further purpose is to automatically time the heating and cooling times of drills, etc. during annealing so as to keep the heat on during a proper annealing period and to reliably cool before removal from the chamber.

Further purposes will appear in the specification and in the claims.

I have preferred to illustrate one main form only, among the various forms in which my invention may appear, selecting a form which while practical and efficient, has been selected primarily because it well illustrates the principles of the invention.

In the drawings Figure 1 is a diagrammatic illustration of my invention showing the furnace and timing mechanism in side elevation.

Figure 2 is a vertical section partly broken away and omitting intermediate parts of all of the heating coils but one of those which comprise the furnace.

Figure 3 is an enlarged fragmentary longitudinal section of a portion of a furnace showing a single coil and the holder for a single drill in vertical position.

Figure 4 is a broken vertical cross section of a portion of a furnace showing the furnace and drill holder tilted.

Figures 5, 6 and 7 are diagrammatic perspectives of mechanism for controlling application of heat to the furnaces.

In the drawings similar numerals indicate like parts.

The problem to be met and the solution of the problem are so aptly illustrated by explaining conditions found in the art of mak-

ing drills and particularly in the art of making high speed twist drills that the invention will be described in terms of drill manufacture and treatment with the understanding that it is intended to apply wherever similar conditions of discoloration occur and prove objectionable.

In the manufacture of drills there is considerable warping of the drills during the tempering. This occurs with all steel drills but the warping is greater and therefore is more objectionable with the alloy steels used in "high speed" drills than in so-called carbon steel drills and the necessity for grinding the drills to true them is more imperative with the high speed drills.

The grinding must be done after tempering and takes the name off the shank. The name cannot well be replaced without first heat-treating the drill to anneal the shank. It is also desirable generally to have the shank untempered; but the annealing of the shank cannot be effected with any of the methods now in use without discoloration, which objectionably affects the drills, interfering with their sale. My invention finds its most desirable immediate use in annealing without leaving any discoloration.

The difficulty met with drills is greatest with straight shank drills.

My invention contemplates heat treatment within a protected compartment or chamber and within a protective atmosphere, maintaining the drills within the atmosphere not only during the heating, but also during the cooling incident to the annealing process.

Describing the mechanism in general form, I show in Figure 1 a furnace 10 of which one possible form is shown in Figure 2 in connection with a drill holder 11 capable of movement toward and from the furnace. I prefer to heat by high frequency induction through coils 12 supplied with high frequency from a generator 13 through a transformer

14. Across the secondary coil is thrown a capacity 15 and a gap, which may be a quench gap, is inserted at 16. The current is controlled by any suitable mechanism 17 whereby the current is cut off or is reduced after suitable time for heating. This mechanism, 100

shown without detail in Figure 1, may be electrically or mechanically controlled.

It does not matter from the standpoint of my broad invention whether the control be 5 by hand or automatic, and if the latter a time function, such as is effected by a clock or through revolving contacts, or an energy function as through an integrating watt meter, nor whether the time be fixed to agree 10 with the needs for a large number of pieces of the same heat capacity or variable.

The frequency used and the voltage may both be varied greatly, subject to variation 15 of course in the time required for the operation and the frequency differing according to the minimum size of control to be treated as taught by Dr. Northrup in his U. S. Patents Nos. 1,694,791 and 1,694,792. While I deem my duty under the statute to give the 20 best form of this known to me I do not wish to be held to any figures on this question nor even to the frequency and voltage being of the same order as tried out by me, as I consider my invention broader than this and be- 25 lieve that easy tests will determine the voltage and frequency best adapted to heating of individual pieces of work without the necessity even of computation such as has been rendered available by Dr. Northrup. 30 Experiments have shown that both the frequency and the voltage can be quite high, very successful operation being secured at 50,000 cycles and 25,000 volts supplied from mains 18, 18' having a difference of potential 35 of 220 volts.

The coils 12 may be water cooled, as is well known in the coreless induction heating art, and I have intended to suggest this by the use of hollow tubing 19 to which the electric current is connected as at 20 without interfering with the water cooling connections. 40 As the connections for this purpose are well known I have not considered it necessary to illustrate this water cooling attachment.

The coils are preferably enclosed within electrically insulating walls 21 surrounded by a heat insulator 22 so as to reduce electrical, and thermal leakage to a minimum.

Though my invention can be applied and 50 is quite effective in single units intended to treat one drill shank only at a time there is considerable advantage in speed of handling and the cheapness of operation in providing the furnace with a plurality of treating 55 chambers and treating coils so that a corresponding number of "gang" of drills may be treated at the same time. For convenience of illustration I have shown five such compartments, coils and drills, the interior portions 60 of the coils being omitted in Figure 2 from four of the five coils and in Figure 4 from the only coil shown.

At the mouth of each compartment I may 65 provide a seal, very conveniently effected by an asbestos ring 23 which engages with the

surface 24 of the drill when the drill shank 25 lies within the compartment. There is normally a further protection against gas leakage at this point by engagement of the surface 26 of the drill holder against the surface 27 of the furnace unit. 70

Through any suitable piping 28 communicating with the several compartments I fill them with a non-oxidizing atmosphere such as nitrogen and mount the furnace in such a position that the atmosphere will be trapped in the compartments. For an atmosphere lighter than air the openings 29 for drill entry will be located at the lower end of the furnace. Two positions of the furnace are 75 provided for in the drawings, the one the position of Figures 2 and 3 where the furnace lies with the axes of the treating chambers vertical and the other, shown in Figure 4, where the drill axes are inclined, the purpose being in either event to protect against serious leakage of the oxidizing atmosphere through the apertures providing for drill insertion. 80

I have not considered it necessary to illustrate the drill holder in detail. The type used for my tests has been of extremely simple form as a clamp divided along a plane through the axes of the drills. 90

The nonoxidizing atmosphere is furnished 95 from any suitable tank 30 and is controlled by valve 31, the pressure being indicated by a gauge 32.

While with nitrogen as the special atmosphere I locate the furnace so that its openings for drill insertion lie in the lower part of the furnace, if a heavier-than-air atmosphere be used these openings would of course be located in the upper part of the furnace and the drills would be inserted from above. 100

One convenient time regulator for determination of the time during which the current shall be applied and also the time during which the current shall be cut off for cooling purposes is shown in Figure 5. In it the electromagnets 33 and 34 are arranged at the end of a plunger chamber within which an armature 35 is free to move guided by a rod 36. The opposite end of the rod carries a plunger 37 which operates in an oil cylinder 110 38 and in which leakage is provided through or around the piston so that the piston and oil cylinder are effective as a dash-pot to retard movement of the plunger. 115

The electromagnets are supplied at 39, 40, 120 41 through switches 39², 39² and 40² with current from a low tension source such as the individual 110 volt parts making up the 220 volt supply. The electromagnets are successively engaged and opened by a series of contacts 42 and 42' upon continuously rotating contact discs. The engagements of contacts 42 and 42', both shown as connected with the "neutral" 40, with brushes 43, 44 for electromagnets 36 and 37 are timed to 125

alternate, with or without a time gap between contacts for the different electromagnets. Obviously the relative times and lengths of time of excitation of the two electromagnets may be designed to offer any time relation between them by varying the angular relative extensions of the contacts 42 and 42'. The relative strengths of the electromagnets are also capable of adjustment 10 by the use of rheostats 45 and 46.

The operation of the plunger makes and breaks the high frequency circuit by any suitable means of which I have diagrammatically illustrated a contact 47 carried by the 15 plunger and connected with one side of the circuit as engaging during a part of the stroke of the plunger with a contact 48 connected with the other side of the circuit and spring pressed at 49 to maintain engagement 20 through a part of the movement of the plunger.

The contacts and contact interruptions may be made unequal in time to any extent desired, even where there is equal time of energization of the electromagnets, by varying the extent of "follow" of the contact 48 to maintain engagement with contact 47, so that this furnishes another means whereby an interruption in line 50, 51 may be opened or closed 25 during any predetermined or adjustable part of the entire stroke of the plunger.

The various means of predetermination and adjustment give complete control of the comparative time of heating the charge and 30 for cooling and changing the charge.

In Figure 6, I have shown a motor-operated contact device for closing and opening the interruption in line 50, 51.

A motor 52 through any suitable gear reduction 40 53 and change speed device 54 rotates a contact arm 55, connected with portion 50 of the line, so that this arm will engage contacts 56 connected with the part 51 of the line.

45 The angular length of the contacts 56 and their number per rotation—whether one or many—combined with the speed change mechanism 54 afford a wide range of adjustment in the timing provided. Of these two 50 adjustments variation in the angular length of the contacts 56 affects the relative length of time for heating and for cooling and replacement, but variation by change of the speed adjustment 54 alters both of these times 55 in equal proportion.

My discussion of time variation is not intended to indicate that it is necessary to vary the time in actual practice. Where a furnace is operating upon products of the same 60 character—such as drills—and particularly where these products are nearly of the same size, a standard timing may readily be determined upon and the apparatus will then be designed for this timing without need of variation. The contact mechanisms shown are,

of course, fully operative for such a condition and in order to emphasize this I have illustrated in Figure 7 a clock-operated contact mechanism corresponding otherwise with the mechanism shown in Figure 6, but in which 70 no time variation is provided.

All of the mechanism is intended to be diagrammatic in that they show examples only of mechanism by which the function may be carried out and without intended restriction to the particular forms shown. 75

In operation on the drills, the chambers or compartments are filled with the protective gas, the drill holders are loaded and the shanks of all the drills are inserted within 80 the openings so that the shanks extend into the treating compartments to any desired extent. The extent can be preliminarily determined by the structure of the holder or can be set by an adjustable extent of projection 85 of the drills outside of the holder. Any suitable guides not shown may be used to ensure registration of the drill shanks with the chamber openings.

The current is turned on by hand or by 90 any operating mechanism and is maintained on during the heating part of the annealing operation. The current is then turned off, the drill shanks are allowed to cool in the protective atmosphere and the drills are removed for insertion of a new set of drills. The supply of nitrogen will be but little dissipated and any slight dissipation of the nitrogen may be replaced by a further supply 95 from the tank. 100

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention. 105

Having thus described my invention what 110 I claim as new and desire to secure by Letters Patent is:

1. In a tempering device for tools, the combination of a high frequency coreless inductor coil furnace, heat insulation about the furnace and a non-oxidizing atmosphere within the coil and in the space for the tool, the opening for insertion of the tool into the atmosphere being so located as to retain the atmosphere within the space by difference 115 in density between the non-oxidizing atmosphere and the air. 120

2. In a tempering furnace for tools, a coreless inductor electric furnace coil having a 125 space within the coil for insertion of a tool, a source of high frequency current supply for the coil, contact mechanism operating at predetermined intervals making and breaking the current supply at intervals corre- 120

sponding with the heating and cooling time required for tempering the tool.

3. In a tempering furnace for tools, a coreless inductor electric furnace coil having a space within the coil for insertion of a tool, a source of high frequency current supply for the coil, relatively timed contact making and breaking mechanism closing and opening the supply circuit at intervals corresponding with the heating and cooling time required for tempering the tool and a non-oxidizing atmosphere about the tool during treatment of it.

4. An induction electric furnace for heating tools, comprising a coreless inductor furnace coil having approximately the interior shape and dimension of the tool, means for inserting a non-oxidizing atmosphere about the tool and automatic means for connecting and disconnecting current supply with the coil to space the current connections by a time sufficient for cooling, removal and replacement of the tools.

5. A gang drill-shank-annealing furnace, comprising a plurality of parallel compartments, electric furnace coreless inductor coils within the compartments, a source of high frequency current supply for the coils, a holder for the drills, maintaining them in relative positions corresponding to the positions of the compartments and means for connecting and disconnecting the electric current to and from the coils.

6. In a gang annealing furnace for drill shanks, a plurality of coreless inductor furnaces closed at the top and having openings at the bottom, means for inserting a non-oxidizing atmosphere within the furnaces and a drill holder exposing the shanks and holding the drills in relative positions corresponding to the positions of the furnaces, whereby the drills may be inserted into and removed from the bottom openings without loss of the atmosphere within the furnaces.

7. A high frequency induction electric furnace comprising a plurality of furnace chambers having bottom openings and an inductor coil within each chamber the bottom openings acting as guides to space the drills from the inductor coils, a holder for the drills maintaining them in relative positions corresponding with the positions of the openings and means for inserting a non-oxidizing atmosphere within the chambers.

OVILA JOSEPH BLANCHET.
